Application June 24, 1946, Serial No. 678,824

7 Claims. (Cl. 77—32.3)

1

This invention pertains to drill presses, and more particularly to an electrically controlled press of the repetitious step-drill type.

In drilling deep sections it is necessary to periodically remove the drill from the work piece for cooling of both the drill and work piece and also for chip removal. Depending upon the depth of drill, it may be necessary to remove the tool from the work by elevation of the quill a number of times during the drilling of one piece.

Such repetitious elevations of the quill have heretofore been manually controlled or in some instances hydraulically controlled. In manual control the attendance of the operator is constantly needed, which requires an operator for each spindle used. In using the hydraulic control, much additional equipment is needed, as for example the pump, the hydraulic pressure lines, and the pressure operated control mechanism. Such additional equipment involves a considerable increase in cost of the drill plus rather frequent maintenance operations.

In the present machine the removal and reentry of the drill into the work piece is electrically controlled with the addition of relatively few pieces of equipment to that normally found upon a standard manual drill press. Not only is the resulting machine simplified in construction, but it is more efficient and less likely to get out of repair. Furthermore, the control equipment is substantially self contained and can be incorporated in the drill press without a complete redesign of the unit.

Thus, the object of the present invention is to improve the construction as well as the means and mode of operation of step-drill presses whereby they may not only be more economically and easily assembled, but the parts thereof will be more accessible for inspection and replacement, and be less likely to get out of repair or adjustment.

A further object of the invention is to provide a substantially self-contained control unit wherein the parts are so arranged as to minimize adjustment difficulties.

A further object of the invention is to provide a device of the character described in which the reciprocation of the quill and spindle is fully automatic, including means for controlling movement of the quill upon approach of the drill tool to the work piece.

A further object of the invention is to provide a device of the character described which after operation has been manually initiated will complete through a predetermined number of cycles

2

the complete drilling operation, and return to rest awaiting removal of the operated work piece.

A further object of the invention is to provide a device of the character described having the advantageous structural features and inherent meritorious characteristics and mode of operation hereinafter set forth.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the drawings, wherein are illustrated preferred but obviously not necessarily the only forms of embodiment of the invention,

Fig. 1 is a perspective view of a drill press embodying the present invention.

Fig. 3 is a side view partly in section of the control mechanism looking from the right of Fig. 2.

Fig. 4 is a side view partly in section of the control mechanism looking from the left of Fig. 2.

Fig. 5 is a sectional view on line 5—5 of Figs. 3 and 4.

Fig. 6 is a sectional view on line 6—6 of Fig. 5.

Fig. 7 is a detail view partly in section of the overrunning clutch and one of the drive means therefor.

Fig. 8 is an enlarged detail view of the ratchet sections.

Fig. 9 is an enlarged sectional view of one of the guide rods.

Fig. 10 is a schematic wiring diagram of the electrical control system.

Like parts are indicated by similar reference characters throughout the several views.

In general, the present invention relates to drilling deep holes where the depth to be drilled is in the neighborhood of ten to forty times the diameter of the tool and where the material is such that after a tool penetration of one or two diameters, the tool must be completely withdrawn from the hole to clear chips and to permit coolant to enter the partly drilled hole. The present structure provides automatic fast travel of the tool to the work piece, automatic engagement of the regulated tool feed just before the tool engages the work, and automatic fast retraction of the tool to its starting point after the

tool has penetrated a predetermined distance under influence of the regulated feed. A second operation is then begun in which the tool has automatic fast travel into the work piece and the regulated feed is automatically engaged just before the tool engages the bottom of the hole produced in the previous penetration, and fast retraction of the tool to its original starting point after advancing a predetermined distance under control of the regulated feed, after which a third operation is begun. These repetitive operations continue until the desired depth of hole has been obtained, after which the tool is retracted under fast travel motion to its original starting point and remains there until a new cycle of operations is begun by momentarily manually closing an electrical contact, after putting a new work piece into the fixture.

The number of operations in each cycle and the depth of penetration during each operation is definitely and accurately predetermined by settings which remain constant during extended periods of operation. Furthermore, the particular settings can be accurately duplicated at any later time should the same type of work again be required.

Referring to the drawings, there is mounted upon the base 1 the usual lower column or housing 2, upon which the table 3 is vertically adjustable along the ways or guides 4. Carried by the lower column 2 is a top column 5 upon which the spindle actuating means and feed control units are supported. Mounted in relatively fixed position upon the back of the top column is a motor 6, which through the step pulley 7 and belt 8 actuates the drill spindle and associated mechanism.

Contained within the housing 9 fixedly supported upon the front of the top column 5 is a change speed mechanism, comprising a group of optionally engageable gears which provide a series of relatively "high" spindle speeds, or through the use of a "back gear" arrangement provides a series of relatively "low" spindle speeds. The input shaft of the change speed mechanism is driven by the belt 8 through the step pulley 9. The output of the change speed mechanism is delivered to the drill spindle 11 through a spline connection within the housing which permits continuous rotation of the spindle 11, although in various positions of vertical adjustment.

A secondary change speed mechanism is enclosed within the housing 12, the input for which is taken from the principal change speed mechanism 9. The speed of the output shaft 13 of the secondary change speed mechanism 12 is adjustable by a change of gears therein, but always has a definite predetermined ratio in relation to the speed of the spindle 11. The shaft 13 controls, through appropriate mechanism to be later described, the rate of down feed of the drill spindle 11. The rate of feed of the spindle 11 in relation to its speed of rotation can be accurately determined and preset by this mechanism. Such setting can be maintained throughout extended periods of operations or duplicated at some later date.

Immediately below the change speed mechanisms 9 and 12 is a housing 14 within which the automatic control mechanism is enclosed. This housing is integral with an arm 15 adjustably supported upon the top column 5 by guides or ways 16. The arm 15 further serves as support for the quill 17, within which the drill spindle 11 rotates.

The quill 17 is vertically adjustable relative to its supporting arm 15, providing vertical movement to the drill spindle 11 which is vertically fixed relative thereto. Downward movement of the quill 17 governs the rate of feed of the drill spindle 11 into the work piece. Upward movement of the quill retracts the drill spindle from the work piece preparatory to the next drilling operation.

The rate of downward movement of the quill 17 or rate of feed of the drill spindle 11 is controlled by the secondary change speed mechanism 12 through rotation of its output shaft 13. Slidingly engaged upon the lower end of the shaft 13 by means of a spline 13' is a worm 18 fixedly supported in a housing 19 projecting from the side of the vertically adjustable arm 15. The splined connection of the worm 18 with the shaft 13 permits continuous driving engagement therebetween regardless of the vertical position of the arm 15 and associated housing 19. Meshing with the worm 18 is a worm gear 20 which comprises one element of an overrunning or "free-wheeling" clutch unit 21.

The clutch 21 with its axis transversely disposed relative to the shaft 13 is supported within the housing 19 upon a feed pinion shaft 22. Supported for independent rotation upon a projection 23 of the feed pinion shaft 22 is the operating disc 24 of the clutch. Intermediate the operating disc 24 and worm gear 20 is a driven spider 25, to which is keyed the feed pinion shaft 22 for unison rotation therewith. Carried by the spider 25 are a pair of friction shoes 26 each pivotally mounted at 26' to a link 27, which in turn is pivoted at 28 to the spider 25. Projecting from the outer side of the operating disc 24 is a hub or hollow shaft 29 to which either manual or, in this instance, automatic actuating means is applied to produce fast travel motion of the quill 17 independently of the regulated spindle feed controlled by the secondary speed change mechanism 12. Carried upon the inner side of the operating disc 24 are a pair of spring biased plungers 30 which under certain operating conditions engage the links 27. Under other conditions of operation a pair of rollers 31, also carried upon the inner side of the operating disc 24, engage tail portions 32 of the links 27. The operating disc 24 is also operatively connected with the spider 25 through a lost motion connection comprising an enlarged hole 33 through which the pivot pin 28 projects. The operating portions of the clutch are all enclosed within the worm gear 20 to which is affixed a face plate 34.

In operation, the worm gear 20 is continuously driven at a constant predetermined speed, governed by the secondary speed change mechanism 12. When such speed is less than that of the operating disc 24, the gear 20 turns idly about the feed pinion shaft 22. Under these conditions the operating disc 24 is rotating faster than the worm gear 20 and the pivot pin 28 engages the trailing edge of the enlarged hole 33 to drive the spider 25 and the associated feed pinion shaft 22 at an increased rate of speed. During this period the spring biased plungers 30 with their springs 35 compressed engage the adjacent edge of the links 27, tending to swing the links in a counter-clockwise direction about their pivots 28. Such movement of the links 27, however, is prevented inasmuch as the center pivot 28 of the toggle mechanism 26-28 and feed pinion shaft 22 is being continuously moved forward, preventing 75 alignment of the three toggle centers. Upon in-

terruption or slowing of the forward motion of the operating disc 24, the spring biased plungers 30 are then able to exert their influence upon the links 27 since the center pivot 28 of the toggle is free to move toward dead center position in relation with the other pivots 26' and the feed pinion shaft 22.

Such movement of the links 27 brings the friction shoes 26 into engagement with the inside surface of the worm gear 20 which is rotating at its predetermined speed. The speed of the worm gear 20 being now faster than the speed of the operating disc 24, the friction shoes 26 become positively engaged therewith. Through the toggle mechanism sufficient pressure is produced to prevent slippage of the shoes upon the inner surface of the worm gear 20. Thus, through the friction shoes 26, the worm gear 20 rotates the spider 25 and its associated feed pinion shaft 22 at the predetermined rate of speed.

Upon reverse rotation of the operating disc 24 the rollers 31 carried thereby engage the tail portions 32 of the links 27, causing the links to rotate in a clockwise direction, thereby disengaging the friction shoes 26 from the inner surface of the worm gear 20. The feed pinion shaft 22 is thereby again disengaged from the positive control of the worm gear 20 and placed under control of the operating disc 24. The reverse rotation of the operating disc 24 is transmitted to the spider 25 and associated feed pinion shaft 22 through the pivot pins 28 which now engage the opposite edge of the hole 33.

Carried upon the feed pinion shaft 22 is a feed pinion 36, the rotary motion of which is translated into vertical reciprocatory motion of the quill 17 by rack teeth 37 upon the quill with which the pinion 36 meshes.

By this arrangement the quill 17 and drill spindle 11 may be rapidly moved up or down permitting a rapid traverse of the non-producing portions of the operating cycle, while maintaining a fixed rate of feed in relation to the speed of the drill spindle 11 during the work producing portion of the operating cycle.

In place of the usual hand lever normally used to control the rapid traverse of the quill in manually operated machines, the present drill press employs a power operated means. Secured to the outer side of the clutch housing 19 is an additional housing 38 which serves as a support for a reversible torque motor 39, the axis of which is transversely disposed relative to the feed pinion shaft 22. Driven by the torque motor through a resilient coupling 40 is a worm shaft 41 on the forward end of which a hand wheel 42 projects from the housing 38. Secured to the shaft 41 is a worm 43 which meshes with a worm gear 44 carried by the extended hub 29 of the operating disc 24 of the "free wheeling" clutch previously described. The torque motor 39 provides the necessary power for rapid traverse movements of the drill spindle 11 in either direction and is of such construction that it may be slowed or stalled indefinitely without becoming overheated.

Under influence of the torque motor 39 the operating disc of the clutch 21 causes a fast advance or rapid traverse of the spindle 11 until the spindle meets resistance to its advance or downward movement. Any resistance encountered by the spindle 11 in its advance causes a reduction in speed of the operating disc 24 to an amount less than the speed of the worm gear 20 resulting in the engagement of the clutch 21 with the worm gear 20. This places the spindle 11 under

control of the regulated feed as determined by the secondary speed change mechanism 12. During the period of regulated feed the torque motor 39 rotates at the same speed due to the braking effect thereon of the clutch engaged worm gear 20. Upon reversing the direction of rotation of the torque motor 39, the operating disc 24 reverses its direction of rotation, and the rollers 31 carried thereby disengage the clutch 21 from the worm gear 20. This permits the torque motor 39 to again assume control of the feed pinion shaft 22, producing a rapid traverse or fast retraction of the quill spindle 11 from the work piece.

In order to artificially create resistance to the downward movement of the drill spindle 11 prior to the time it engages the work piece an electro-magnetically actuated brake upon the feed pinion shaft 22 is used. Secured to the outboard end of the feed pinion shaft 22 adjacent the feed pinion 36 is a brake drum 45 keyed to the shaft 22 for unison rotation therewith. A cover plate 46 is secured to the outer surface of the brake drum enclosing the end of the shaft 22. Surrounding the periphery of the brake drum 45 is a relatively resilient brake band 47, one end of which is positively anchored at 48 to the supporting arm 15. The opposite end 49 of the brake band is adjustable toward and from the anchor 48 to engage and disengage the brake band and the brake drum. The brake band is adjusted by a toggle lever comprising a link 50 to which the adjustable end 49 of the brake band is secured, and a link 51 one end of which is pivotally anchored at 52 to the supporting arm 15, the other end being pivotally connected at 53 to the link 50.

To engage the brake band 47 with the drum 45, the pivot 53 which is normally somewhat above dead center relative to the points 49 and 52, is brought into substantially dead center relation therewith. This is accomplished by means of a bell crank lever 54 pivotally secured at 55 to the supporting arm 15, the upper end 56 of which is pivotally secured to the solenoid 57. The other end 54' of the bell crank lever is pivotally interconnected with the pivot point 53 by the connecting link 58. Thus when the solenoid is energized, the lever 54 is rocked in a clockwise direction about its pivot 55 which is translated into a vertical pull upon the pivot 53 of the toggle mechanism by the connecting link 58. Actuation of the brake band 47 by the solenoid 57 creates sufficient resistance to rotation of the feed pinion shaft 22 to cause the clutch 21 to engage the worm gear 20, placing the feed pinion shaft under control of the secondary speed change mechanism 12 producing the predetermined regulated rate of feed of the quill 17 and drill spindle 11. The brake band 47 does not however create sufficient rotational resistance to prevent operation of the feed pinion shaft 22 under the influence of the regulated feed produced by the secondary speed change mechanism 12. During the period of regulated feed operation the brake band 47 merely slips upon the brake drum 45.

The mechanism for automatically controlling the reciprocatory motion of the drill spindle 11 and quill 17 is contained within the housing 14 supported upon the arm 15. Fixed to the top of the quill 17 for unison reciprocatory motion therewith is a collar 60. Carried by the collar in spaced relation with the front of the quill 17 are a pair of oppositely projecting arms 61 and 62. To the arm 61 there is secured a spindle return

switch 63 which when closed actuates a mechanically held contactor 82 to energize the torque motor 39 in reverse direction to retract the spindle 11 to its upper limit of travel. The point at which the return switch 63 is closed varies with each succeeding penetration of the spindle 11 until a complete cycle of operation has been completed. The point at which the switch 63 energizes the torque motor 39 is determined by a solenoid operated tripping device comprising a sliding depth gage 64 mounted for reciprocatory motion upon a rod 65 fixedly supported at its upper and lower extremities in the walls of the housing 14. This rod 65 is parallel with the spindle 11, but both laterally and forwardly offset relative thereto. The depth gage 64 determines the depth of penetration of each successive drill feed operation, and is automatically lowered upon the rod 65 at the completion of each drill feed operation preparatory for the next such operation.

To maintain the depth gage 64 in a predetermined position upon the rod 65 for each succeeding drill feed operation, the rod is provided with a ratchet like templet 66, the distance between the teeth 67 thereof being equal to the desired penetration for each drill feed operation. The spacing of the teeth may be uniform, or may be varied with a greater spacing at the upper end to permit a greater penetration of the drill at the beginning of the operation, becoming shorter as the depth of the hole increases with more chip and coolant difficulties. The distances between the teeth are generally about equal to the diameter of the drill being used.

The templet 66 is sectional, the sections being readily interchangeable, one for another, to provide different spacing intermediate succeeding teeth. The sections may contain a series of equally spaced teeth, or if desirable for a particular application, the spacing of the teeth may vary with a single section. The several templet sections are retained in the rod 65 by an undercut groove 68 therein. The shoulders 69 thereof engage the flanges 70 of the templet sections. When assembled the teeth 67 of the templets which project from the surface of the flanges 70 lie within the slot 71 in the bar 65. The vertical location of the templets relative to the rod 65 is maintained by the use of spacers 72. The lowermost spacer is held in adjusted position by a set screw 73 threaded through the wall of the housing 14 into engagement therewith.

Carried by the depth gage 64 is a pawl 74 which cooperates with the teeth 67 of the templets to maintain the gage in a predetermined adjusted position. The pawl 74 is periodically moved out of engagement with the teeth 67 by momentarily energizing a solenoid 75 carried upon the gage 64. Such movement of the pawl 74 permits the gage to drop down the rod 65 the distance to the next succeeding tooth into which the pawl is urged under influence of the spring 76 about the rock shaft 77 upon which the pawl is mounted. By this means the gage is indexed downwardly on the rod 65 by predetermined increments, each increment being equal to the depth to be drilled during that portion of the operating cycle.

Rotational movement of the depth gage 64 upon the rod 65 is prevented by a dog screw 78 the end of which rides in the slot 79 in the back of the rod 65. A shoulder 80 is provided upon the back of the gage 64 to engage the actuating member 81 of the spindle return switch 63. Actuation of the member 81 upon engagement

with the shoulder 80 closes the switch 63 which simultaneously energizes the gage solenoid 75 and actuates the mechanically held contactor 82 to energize the torque motor 39 in reverse direction. Energization of the solenoid is momentary since the gage immediately drops to its next position as determined by engagement of the pawl with the next succeeding tooth. The shoulder 80 of the gage being moved away from the actuating member 81 of the switch, the switch is returned to its normally open position.

The torque motor 39 remains energized in reverse direction and raises the spindle 11 to its upper limit of travel motion. Upon reaching such upper limit, the torque motor is then again reversed to advance or lower the spindle to drilling position. Actuation of reversing contactor 82 to change the direction of rotation of the torque motor is controlled by a switch 83 depending from the top surface of the housing 14. The actuating member 84 thereof is engaged by a tail portion 85 of a latch piece 86 pivotally carried upon the arm 61. The latch 86 is spring biased in a clockwise direction by the spring 87 and plunger 88 supported within the arm 61. Under normal operating conditions the latch is maintained in its spring biased position.

The final drilling operation is determined by the location of a final depth stop 89 comprising a split collar which is clamped in adjusted position upon the bar 65 by means of a screw 90. Rotation of the stop collar relative to the rod 65 is prevented by engagement of a dog screw 91 within the guide slot 79 in the back of the rod. Secured to the stop 89 in the path of travel of the latch 86 is a leaf spring 92. As the latch 86 contacts the leaf spring, it is rotated about its pivot into engagement with an undercut notch 93 in the bottom surface of the gage 64. The gage having completed its downward travel motion, is supported in the last tooth 67 adjacent the stop collar 89 in position to receive the latch 86 when pushed therein by the spring 92. This position of the depth gage 64 signifies the completion of the last drilling operation of the cycle. Upon subsequent closing of the spindle return switch 63, the spindle 11 and quill 17 are retracted to their upper limit of travel motion, and by means of the latch 86 which moves in unison with the quill 17, the gage 64 is also lifted to the top of the rod 65 preparatory to the beginning of a new cycle of operation.

The latch 86 having been moved in a counter-clockwise direction into the notch 93, it is held in such position by the weight of the depth gage 64 until subsequent relaxation of the gage's weight thereon. While held in its rotated position, the tail portion 85 thereof is swung out of alignment with the actuating member 84 of the spindle advance switch 83. Thus the spindle and quill, after the last retraction is held in retracted position by the torque motor 39 until the spindle advance switch 83 is manually closed to start a new cycle of operation.

As previously explained, the vertical travel speed of the quill, as determined by the torque motor 39 and the secondary speed change mechanism 12, is regulated by energization of the brake solenoid 77 and actuation of the brake 47. Energization of the brake solenoid is in timed relation with the energization of the gage solenoid 75 and the spindle return switch 63. To provide for the timed relation between the energization of the various controls, another guide rod 94 is supported within the housing 14 in a

plane parallel with, but forwardly offset relative to the spindle 11 and quill 17. The guide rods 65 and 94 are located in opposite laterally offset planes relative to the spindle and quill.

Carried near the outer end of the arm 62 which projects from the collar 60 is a normally open brake switch 95, the closing of which energizes the brake solenoid 57. The switch is closed upon engagement of its actuating member 96 with a brake switch tripping device slidingly supported upon the rod 94. Also carried upon the extremity of the arm 62 is a latch 98 normally retained upon its pivotal mounting 99 in a substantially vertical position. Intermediate the latch 98 and the brake switch 95 is a screw 100 projecting somewhat below the level of the arm 62. The projecting end of the screw 100 terminates in substantially the same plane as the actuating member 96 of the brake switch 95.

The tripping device 97 comprises a pair of collars 101 and 102, each of which is counterbored at their inner ends to receive a compression spring 103. The lower collar 102 carries a set screw 104, the inner end of which projects within the guide slot 105 in the rod 94. On the opposite side of the collar is a vertical hole 106, tapped to receive the end of an adjusting bolt 107 which transfixes the upper collar 101. This bolt 107 maintains a fixed maximum spacing intermediate the collars 101 and 102. A projection 108 upon the upper collar 101 extends into the path of travel of the switch actuating member 96, which upon engagement therewith closes the brake switch 95 and by means of the solenoid 57 actuates the brake 47. The compression spring 103 has sufficient tension to cause operation of the switch actuating member 96 without collapsing. Simultaneously with the operation of the switch actuating member 96, the projecting end of the screw 100 engages the top of the upper collar 101, thereby relieving the switch actuating member 96 of excessive pressure as the quill 17 and associated collar 60 descend under the control of the secondary speed change mechanism 12.

The pressure screw 104 in the lower collar 102 creates sufficient resistance to movement to prevent the lower collar 102 from sliding downwardly under the weight of the tripping device, or under the pressure exerted by the switch actuating member 96. The frictional resistance of the lower collar is also sufficient to permit the collapsing of the spring 103 under the downward pressure exerted by the screw 100 upon the top surface of the upper collar 101. Upon collapsing of the spring 103, the gap intermediate the upper and lower collars 101 and 102 is closed, the upper collar 101 bearing directly upon the lower collar 102. The frictional resistance of the lower collar 102 is not sufficient to withstand this condition, resulting in a downward movement of the entire tripping device 97 under the pressure created by the downward movement of the quill 17 as transferred through the arm 62 and screw 100 to the upper collar 101 of the tripping device.

Upon completion of the particular drill feed operation and the retraction of the spindle 11, the lower collar 102 of the tripping device remains in its newly adjusted position such position representing the actual depth of the drilled hole in the work piece. As the spindle 11 and quill 17 are retracted to their upper limit of travel motion, pressure upon the upper collar 101 is relieved, permitting the compression spring 103 to again expand and raise the upper collar 101

to its maximum height relative to the lower collar as is determined by the adjustment of the bolt 107. The tripping device 97 is now in condition for the next succeeding portion of the operating cycle.

The upper collar 101 and its projection 108 having been raised relative to its location at the completion of the preceding drilling operation, it will upon the next succeeding downward motion of the spindle, cause the brake switch 95 to close, actuating the brake 47 slightly in advance of the moment that the drill engages the bottom of the previously drilled hole in the work piece. Actuation of the brake causes the downward motion of the spindle to change from rapid traverse movement under control of the torque motor 39 to the regulated drill feed under control of the secondary speed change mechanism 12. This change in spindle feed takes place just before the drill engages the bottom of the hole as drilled in the work piece during the preceding portion of the cycle.

A final stop 109 comprising a split collar similar to the stop collar 89 is adjustably supported upon the rod 94 by means of a screw 110. Affixed to the stop collar 109 is a leaf spring 111 which projects upwardly into the path of travel of the latch member 98. Upon completion of the last drill feed operation as determined by the location of the stop 89, the tripping device 97 will have been pushed downwardly upon the rod 94 into engagement with the stop collar 109 by the arm 62 and screw 100. At this point, the leaf spring 111 urges the latch 98 into engagement with the re-entrant notch 112 on the upper collar 101. Upon the final retraction of the quill 17 and arm 62 to complete the cycle of operation, the tripping device 97 will be moved upwardly on the rod 94 preparatory to the starting of a new cycle of operation.

Adjustably secured in the top of the housing 14 is a depending latch trip rod 113 which returns the latch 98 to its normal position thereby releasing the tripping device 97. The latch 98 having been swung in a counterclockwise direction by the leaf spring 111, the tail portion 114 of the latch projects beneath the end of the trip rod 113. As the latch is raised the tail portion 114 engages the end of the trip rod 113 and is returned to its normal vertical position by the cam surface 115. When this occurs, the latch is disengaged from the notch 112 of the tripping device 97 leaving the tripping device in its adjusted position upon the rod 94. The trip rod 113 is so adjusted by means of a set screw 113' that the engagement of the latch therewith occurs at a point corresponding to a slight elevation over and above the top surface of the work piece. By such adjustment, the brake switch 95 is closed to energize the brake and change the spindle travel from rapid traverse to regulated feed slightly before the drill engages the work piece.

During the final retraction of the drill, both the tripping device 97 and the depth gage are elevated from their lowermost positions and are left in position to control the initial operation of the next succeeding cycle.

Attached to the machine at some point within convenient reach of the operator is a four button push button control station 116 (Fig. 10). When necessary, complete manual control of the machine is obtained through the use of these four push buttons.

Connected to the power lines is an electromagnetic "across the line" motor starter 117 of which there are several makes readily obtainable

upon the open market. The starter magnet is energized by depressing the start button 118. Internal wiring within the starter 117 provides a holding circuit for the magnet after it is once energized by the momentary closing of the button 118. The circuit to the main motor 6 is then completed through wires 119, 120, and 121. Connected in parallel with the main motor 6 by means of wires 122, 123, and 124 is the mechanically held reversing contactor 82 to which the torque motor 39 is directly connected. The direction of rotation of the torque motor 39 is controlled by the selective energization of the advance coil 125 or the return coil 126 in the reversing contactor 82. Also connected through the magnetic starter 117 is a transformer 127, the output of which is supplied to the several control circuits.

After locating the work piece to be drilled, the operator momentarily closes the start button 118 which energizes all of the high voltage circuits. The main motor 6 is thereby put in operation, which through the primary change speed mechanism 9 rotates the spindle 11 at a preselected speed. Closing of the start button 118 also energizes the torque motor 39, its direction of rotation being such as to elevate the spindle 11 inasmuch as the return or "up" coil 126 was last energized for completion of the preceding cycle of operation.

To initiate or start the cycle of operation, the operator momentarily depresses a down button 128 which completes a circuit from the transformer 127 through wire 129, switch terminals 130-131, wire 132, to the advance or "down" coil 125 of the contactor 82. The opposite terminal 133 of the coil 125 is connected by wire 134 with the transformer 127 to complete the energizing circuit.

The torque motor 39 being now energized in advance or "down" direction, the spindle 11 is advanced toward the work piece at relatively high speed until the brake switch 95 traveling downwardly in unison with the spindle 11, contacts the brake tripping device 97. Closing of the switch 95 sets the brake 47 by energization of the brake solenoid 57 through a circuit from the transformer 127. Current is supplied by the transformer 127 through wire 129, contact 130, jumper wire 135 to contact 136 of the manually controlled spindle return or "up" switch 137. From the contact 136, wire 138 leads to the brake solenoid 57 from where the circuit is completed by wire 139, switch 95, wire 140, contacts 141-141' in the reversing contactor 82 which are bridged by the contactor when in the advance or down direction, wire 142, contact 133 of the advance coil 125 and wire 134 to the transformer 127.

Upon application of the brake 47, continued downward movement of the spindle 11 is placed under the control of the secondary speed change mechanism 12. The spindle having completed a rapid traverse of the un-productive portion of its travel motion, it is now advanced or lowered at the pre-determined speed of the regulated drill feed.

During such initial downward movement of the spindle the depth gage 64 is lowered in unison therewith, the gage still being supported upon the latch 86. The unison downward movement of the spindle and depth gage continues until pawl 14 enters the first tooth 67 on the rod 65, whereupon continued downward movement of the gage 64 is arrested. Spindle 11, however, continues its downward movement at the reduced speed of the

regulated drill feed until the actuator 81 of return switch 63 engages the shoulder 80 on the gage 64. During this time the latch 86 swings outwardly (in a clockwise direction) under influence of its biasing spring upon release thereof by relaxation of the gage's weight thereon. Upon contacting the shoulder 80, the return switch 63 is momentarily closed to simultaneously reverse the contactor 82 and energize the solenoid 75.

5 Current is supplied to the return coil 126 of the contactor 82 by the transformer 127, wire 129, contact 130 of the switch 128, wire 135, contact 136 of switch 137, wire 143, switch 63, wire 144, contact 145 of switch 137, and wire 146. The circuit 10 is completed from the return coil 126 to the transformer 127 by wire 147, contact 133 of the advance coil 125, and wire 134. Energization of return coil 126 of contactor 82 reverses the direction of rotation of the torque motor 39, to return 15 or elevate the spindle 11 to its uppermost or original starting position.

In parallel with the return coil 126 is the solenoid 75, which upon closing of the switch 63 is also energized by the transformer 127. The solenoid circuit extends from the transformer 127 through wire 129, contact 130 of switch 128, wire 135, contact 136 of switch 137, wire 143, switch 63, wire 144, contact 145 wire 144', contacts 145-146' of switch 137, and wire 148 to the solenoid 30 75. From the solenoid the circuit is completed through wire 148' to the transformer 127. Energization of the solenoid 75 withdraws the pawl 74 from the teeth 67, permitting the depth gage 64 to drop to the next succeeding tooth 67 with which 35 the pawl 74 is re-engaged to retain the gage 64 in position for the next succeeding portion of the operating cycle.

The spindle travel being reversed upon closing of the switch 63, the spindle is elevated or retracted until it reaches its upper limit. Upon 40 approaching its upper limit, the tail portion 85 of the latch 86 engages the actuating member 84 of the spindle advance switch 83 secured to the upper surface of the housing 14. Closing of the 45 advance switch 83 energizes the advance coil 125 of the contactor 82 thereby reversing the direction of rotation of the torque motor 39, which thereupon lowers or advances the spindle 11 by rapid traverse into proximate relation with the work piece, the rapid traverse of the spindle being 50 terminated by the closing of the brake switch 95.

Closing of the advance switch 83 completes a circuit to the advance coil 125 from the transformer 127 by wire 129, contact 130 of switch 128, wire 149, switch 83, wire 150, contact 131 of switch 128, and wire 132. The return side of the circuit is completed from contact 133 of the advance coil 125 through wire 134 to the transformer 127.

55 The automatically operated spindle advance or down switch 83 is in parallel with the manually controlled down switch 128. The manually controlled "up" switch 137 is in a parallel circuit with the automatically operated spindle return or "up" switch 63 insofar as control of the reversing contactor 82 is involved. The manual switch 137 does not however control energization of the gage solenoid 75. The gage 64 must be retained in its automatically adjusted position if the machine is 60 to be returned to automatic operation. If the solenoid 75 were manually energized by depression of the "up" switch 137, the gage 64 would be dropped to the final stop 89 and the spindle would continue its next downward movement until it reached the equivalent of the final drilling

operation without the necessary retractions for cooling and chip clearance. For this reason the control circuit is so arranged that the gage 64 remains in its automatically adjusted position notwithstanding manual control of the spindle by depression of the "up" button 137. The gage 64 and its control solenoid 75 are actuated only upon closing of the spindle return switch 63. Thus should it be necessary or desirable to reverse the direction of the spindle travel prior to the time of automatic reversal thereof, such a change may be accomplished manually by depressing the appropriate manually controlled switch.

After completion of the drilling operation, the spindle 11 is returned to its uppermost position, and with this last retraction of the spindle the depth gage 64 and brake tripping device 97 are raised the brake tripping device being left in position for the first operation of the next cycle. The latch 86 being engaged with the depth gage 64 during this final upward movement, the tail portion 85 is swung out of line relative to the actuating member 84 of the advance switch 83. The advance switch 83 is therefore not closed, and the torque motor remains energized in the up or return direction, thereby holding the spindle at its uppermost limit of travel.

The spindle remains in this position while the finished work piece is being removed and a new work piece is being inserted in the machine. After insertion of the new work piece, a new cycle of operation is commenced by the manual depression of the down button 128 as previously described.

Should the completion of the drilling operation on the work piece coincide with completion of the day's work, or for any other reason, the next operating cycle is not to be immediately started, the motors 6 and 39 are de-energized by depression of the stop button 151. Opening of the switch 151 de-energizes the holding circuit of the magnetic contactor 117, thereby opening the main power supply line to the machine. The start and stop buttons 118 and 151, respectively, control the contactor 117 through the wires 152, 153, and 154, wire 152 being common to both buttons. The start circuit comprises wires 152 and 153, while the stop circuit consists of wires 152 and 154.

Not only does a machine of the type described herein represent a reduction in the initial cost as compared with machine employing hydraulic controls, but it has far greater accuracy and dependability. The controls for the present machine are not subject to variation due to change in temperature, nor are they dependent upon the continued maintenance of a predetermined fixed pressure. Once adjusted, the present controls will repeatedly operate at the identical point, affording almost instantaneous response in the machine operation. Once a particular job is set up on the machine, the settings may be duplicated at any time in the future when it becomes necessary to run the same job again. The resetting of the controls is accomplished without the necessity of step-by-step adjustments thereof.

The machine is adaptable for many different types of drill operations under varying conditions, its flexibility being in no way sacrificed for its positiveness of action, and simplicity of construction and operation.

While the control system has been described in connection with its application to a drill press, it is equally applicable to other types of machine tools having a reciprocating tool member mov-

able through a progressively increasing range of travel motion.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. An electrically operated drill press of the automatic step-drill type wherein an operating cycle consists of a series of alternate up and down movements of the drill spindle and tool out of and into a work piece including means for automatically controlling the reciprocations of the drill spindle and arresting motion of the spindle at the completion of an operating cycle, comprising a fixed electrical switch relative to which the spindle reciprocates, a pair of traveling electrical switches mounted on the spindle for unison travel motion therewith, a pair of traveling stops adjustably mounted upon the drill press relative to which the spindle reciprocates, means for automatically adjusting said stops upon engagement of the traveling switches therewith, one of said stops being adjusted in unison with the downward movement of the spindle, the other of said stops being adjusted to a predetermined position independently of the travel movement of the spindle, means for retarding the downward movement of the spindle upon engagement of one of said traveling switches with one of said stops, means for reversing the travel motion of the spindle upon engagement of the other of said traveling switches with the other of said stops, oscillatory means carried by the spindle normally engaging the fixed switch to reverse the direction of the spindle at its upper limit of travel motion, a second pair of stops fixed in predetermined adjusted position relative to which the spindle reciprocates, means actuated by the approach of the traveling switches to the second pair of stops for interconnecting the traveling stops with the spindle for unison upward movement therewith, and simultaneously moving said oscillatory means out of the path of the fixed switch thereby stopping the spindle at its upper limit of travel motion, and means for releasing the traveling stops from the spindle in predetermined positions preparatory to the starting of a new cycle of operation.
2. In a drill press of the automatic step-drill type wherein an operating cycle comprises a series of reciprocatory movements of the drill spindle and tool into and out of a work piece during which cycle the drill spindle has alternate periods of fast and slow vertical travel motion, an electrical operating system therefor including a reversible torque motor intermittently energized in alternate directions to raise and lower the spindle during periods of relatively fast travel

motion, a continually energized uni-directional drive motor intermittently connected to the drill spindle to lower said spindle at a relatively slow uniform rate of speed, an electrically controlled clutch alternately subjecting the spindle to the influence of the torque motor and the uni-directional drive motor, and energizing means for the electrically controlled clutch comprising an electrical switch, a laterally projecting arm carried by the spindle upon which the switch is mounted, a vertically expansible switch tripping device, a stationary supporting rod therefor relative to which the spindle reciprocates and upon which the tripping device is vertically adjustable by engagement of the laterally projecting arm therewith, the construction and arrangement being such that upon contact of the switch with the tripping device the electrically controlled clutch is energized subjecting the spindle to the control of the uni-directional drive motor to lower the spindle at the relatively slow uniform rate of speed and simultaneously therewith compress and lower the tripping device by the engagement of the laterally projecting arm therewith.

3. In a drill press of the automatic step-drill type wherein an operating cycle comprises a series of reciprocatory movements of the drill spindle and tool into and out of a work piece, a control system therefor including power means for lowering the spindle at a relatively high rate of speed during the initial portion of its downward movement, additional power means for lowering the spindle at a relatively low uniform speed, the rate of which is fixed relative to its speed of rotation, electrically controlled means alternately subjecting the spindle to the control of the first and second power means, electrically controlled means responsive to movement of the spindle for reversing the first power means to retract and advance the spindle at the relatively high rate of speed, means for energizing the respective electrical control means comprising a plurality of bodily movable electrical switches one for each of said control means, and a plurality of bodily movable tripping devices with which the switches cooperate, means for moving the tripping devices and switches in accordance with the movement of the drill spindle and tool relative to the work piece to thereby control the reciprocatory movements of the spindle and tool, and stop means adjustably determining the completion of the operating cycle.

4. In a drill press of the automatic step-drill type wherein an operating cycle comprises a series of reciprocatory movements of the drill spindle and tool into and out of a work piece, a control means including a reversible torque motor operative to raise or lower the spindle at a relatively high rate of speed, a conventional drive motor operative to lower the spindle at a relatively low uniform speed, a clutch alternately interconnecting the spindle with the torque motor and the conventional motor, electrically controlled means for actuating the clutch, electrically controlled means for reversing the torque motor in optionally timed relation with the actuation of the clutch, a plurality of switches fixedly carried upon the spindle for intermittently energizing the electrically controlled means, a plurality of vertically adjustable gages cooperating with the switches to actuate said switches, means carried by the drill spindle for adjusting said gages downwardly in accordance with the movement of the tool into the work piece, a third switch fixedly mounted upon the drill press rela-

tive to which the spindle reciprocates for energizing the electrically controlled reversing means for the torque motor in predetermined relation with the energization of the reversing means by one of the plurality of switches, and vertically adjustable stop means determining completion of the operating cycle including means for detachably engaging said gages with the spindle for return movement to their initial position.

5. In a drill press of the automatic step-drill type wherein an operating cycle comprises a series of reciprocatory movements of the drill spindle and tool into and out of a work piece during which cycle the drill spindle has alternate periods of fast and slow vertical travel motion, an electrical control system therefore including a first power means for vertically actuating the spindle during its period of fast travel motion, a second power means for actuating the spindle during its period of slow travel motion, electrically operated means controlling actuation of the spindle by the first or second power means, and means for energizing the electrically operated control means comprising a laterally projecting arm carried by the spindle, a switch supported thereon for unison travel motion with the spindle, and means for actuating the switch at predetermined intervals including a stationary guide rod, the axis of which is parallel to the spindle and relative to which the spindle reciprocates, a two piece expansible and contractible sleeve frictionally engaged therewith, an expansion spring intermediate the two parts of the sleeve against the tension of which the sleeve is compressible upon engagement of the switch and laterally projecting arm therewith, the construction and arrangement being such that pressure of the arm upon the sleeve overcomes the friction thereof and lowers the sleeve in unison with the spindle, and means for limiting the expansion of the sleeve upon removal of pressure therefrom.

6. In a drill press wherein an operating cycle comprises a series of vertical reciprocatory movements of the drill spindle and tool into and out of a work piece, and automatically adjustable depth gage therefor including a vertically adjustable gage member, a support therefor the axis of which is parallel with the drill spindle and with which the gage member has sliding engagement, a re-entrant longitudinally disposed groove therein, a series of differentially spaced ratchet teeth removably engageable therein, a spring tensioned pawl pivotally supported upon the gage member for tensioned engagement with the respective ratchet teeth, electrically operated means for withdrawing the pawl from the ratchet teeth to permit the gage member to move downwardly upon the support until arrested by engagement of the pawl with the succeeding downwardly spaced ratchet tooth, and means for energizing the electrically operated means in predetermined relation to the spindle position comprising an arm carried by the spindle for unison travel motion therewith, and projecting laterally in overhanging relation with the gage member, a switch fixedly attached to the arm, and means engageable with the gage member upon contact of the arm therewith for actuating the switch, the construction and arrangement being such that actuation of the switch energizes the electrically operated pawl control means.

7. In a machine tool having a predetermined cycle of operation, a reciprocatory tool member, means for determining the extent of reciproca-

tory movement of the tool member comprising an adjustable gage member, a ratchet bar upon which the gage member is slidably adjustable, the ratchet teeth of said bar being differentially spaced in predetermined relation, means for interchanging the ratchet teeth for others of different spacing, a detent on the gage member cooperating with the ratchet teeth to retain the gage member in progressively changing predetermined position upon the bar, electrically operated actuating means for the detent, means actuated by the reciprocatory movement of the tool member for energizing the detent actuating means, the construction and arrangement being such that the gage member is progressively moved along the bar by a step by step movement in accordance with the spacing of the ratchet teeth therein, and means for determining the

completion of an operating cycle and simultaneously therewith returning the gage member to its initial position.
